UNITED STATES PATENT OFFICE.

FRANK H. JOHNSTON, OF CHICAGO, ILLINOIS, ASSIGNOR, BY MESNE ASSIGNMENTS, TO ACME CARD SYSTEM COMPANY, OF CHICAGO, ILLINOIS, A CORPORATION OF ILLINOIS.

VISIBLE INDEX.

Application filed April 30, 1924. Serial No. 709,953.

This invention relates to improvements in visible index, and is directed more particularly to a visible index in which the index cards are supported in overlapping spaced-apart 5 relation on a frame.

My invention in its particular embodiment, comprises an auxiliary sheet, which is adapted to be detachably mounted on and supported by the hangers supporting the index cards, 10 one of the features of the invention being that the auxiliary sheet can be mounted on and removed from its hanger without disturbing the position of the index card mounted on the same hanger, and without removing the 15 hanger from the frame.

In the drawings:

Fig. 1 is a side elevational view of a frame, having overlapping index cards mounted therein, and illustrating the mounting of the 20 auxiliary sheet.

Fig. 2 is a perspective view, showing the relative positioning of the master card and auxiliary sheet on the hanger.

Fig. 3 is a second perspective view illustrating the manner of mounting the auxiliary sheet on the hanger.

Referring in detail to the drawings, 1 designates, as a whole, a metal frame having the central web portion 2 which may be turned inwardly on upper and lower edges as shown at 3 and 4. The edges of the web 2 may be covered by the flanges 5 which are riveted or otherwise securely attached to the web 2, as shown at 6. These flanges are offset upwardly to provide 35 side guide channels 7, and the arrangement is such that one or both sides of the web may be provided with these channelled guides 7. The flanges at one edge of the web may be provided with pintles 8, which are adapted to 40 be hung on a suitable stand or in any suitable bracket allowing pivotal movement of the entire frame.

The hangers 9 which may consist of flexible metal are return-bent, as shown at 10, to space 45 the cards a predetermined distance apart, and terminate in the offset projection 11. The hangers 9, being flexible, are adapted to be contracted centrally to be placed in the channelled guides 7, or removed therefrom. The 50 clips 12, which are preferably of metal, are attached to the top of the index cards 13, and are provided with eyes through which the ends 11 of the hangers are adapted to be threaded.

55 Referring now to the particular feature of

this invention, it is, at times, necessary and desirable to employ an auxiliary index card or sheet 14, for the purpose of incorporating data thereon when the master card 13 has been filled and it is necessary to retain same in the 60 file. The auxiliary data-containing card or sheet 14 may also be used where it is desirable to remove the sheet 14 from the index, for instance, by salesmen, and then later replace same. Data such as current prices, record 65 of calls, etc., may be carried by this auxiliary sheet, while the master card may contain permanent data.

The sheet 14 is preferably a double sheet folded as shown, and the folded edge cut away 70 as shown at 15, inwardly from its edges to provide cutaway portions, the inner edges of which are adapted to be hung on the ends 11 of the hanger 9. Thus, it will be seen that the auxiliary sheet can be instantly mounted 75 on and removed from the hanger without removing the card or hanger from the frame, or in any way disturbing the set or positions of adjacent auxiliary sheets, or the master cards or hangers.

I have shown the auxiliary sheet as having cutaway portions. I do not wish to limit myself to cutaway portions, as the sheet may be otherwise slotted or apertured to provide a positive means for detachably mounting the 80 sheet 14 on the hanger. It is obvious that the auxiliary sheet may be mounted either in front or in back of the master card and by superimposing one auxiliary sheet over another, more than one auxiliary sheet may be 85 mounted on the same hanger.

I have shown my invention as applied to frames. It must be understood that in using the expression "frames", I mean to include various types of frames, used individually 90 or in multiple, supported in either a vertical position on a stand, or in a horizontal position. In other words, the essence of the invention is in the provision of the auxiliary card, to be used with visible index equipment 95 mounted in any suitable support, such as the frames shown and described, slideable drawers mounted in cabinets, etc.

I claim as my invention:

1. In a visible index, the combination with 100 a frame, of a flexible hanger having return-bent ends detachably mounted in said frame, an index card detachably mounted relative to the return-bent ends of said hanger by hinge-like elements cooperating between the 105

hanger and card, a folded index member auxiliary to said index card detachably mounted on the return-bent ends of the hanger, being supported solely by its folded edge, and mountable on, or removable from, the return-bent ends of the hanger without disturbing the position of said index card or hanger.

2. In a visible index, the combination with 10 a frame, of a flexible hanger having return-bent ends detachably mounted in said frame, an index card having detachable cooperative engagement with the return-bent ends of said hanger by hinge-like elements cooperating

15 between the hanger and card, a folded index member auxiliary to said index card detachably mounted on the return-bent ends of the hanger, being supported solely by the engagement of its folded edge with the return-

20 bent ends of the hanger and mountable on, or removable from, the return-bent ends of the hanger without removing the card from the hanger or the hanger from the frame.

3. In a visible index, the combination with 25 a frame, of flexible wire hangers detachably mounted in said frame each having return-bent ends, index cards having detachable cooperative relationship with the return-bent ends of said hangers, folded auxiliary index

30 members mounted on the portions of the return-bent ends of the hangers projecting beyond the portions on which said index cards are mounted, said folded index members being supported solely by supporting por-

35 tions at the ends of the line of fold, and mountable on, and removable from, the re-

turn-bent ends of the hangers without disturbing the position of the cards or hangers.

4. In a visible index, the combination with 40 a frame, of flexible wire hangers detachably mounted in said frame each having return-bent ends, index cards having detachable cooperative engagement with the return-bent ends of said hangers, and folded auxiliary index sheets removably mounted on the 45 return-bent ends of the hangers and independently removable therefrom, said folded sheets being supported on said return-bent ends by the engagement of supporting portions at the ends of the line of fold with said 50 return-bent ends.

5. In a visible index, the combination with a frame, of flexible wire hangers detachably mounted in said frame each having return-bent ends, index cards having detachable cooperative engagement with the return-bent ends of said hangers, and folded auxiliary index sheets removably mounted on the 55 return-bent ends of the hangers and independently removable therefrom, said folded sheets being supported on said return-bent ends by the engagement of supporting portions at the ends of the line of fold with said 60 return-bent ends, said folded index sheets being provided with cut-away portions on 65 their folded edge extending to their lateral edges to permit engagement and disengagement of said folded sheets from the return-bent ends of the hangers without removing the index card from the hanger or the hanger 70 from the frame.

FRANK H. JOHNSTON.
